COMBINED FLOWER POT HOLDER AND BRACKET THEREFOR

William H. Michaels, 3568 Independence Road,
Cleveland, Ohio 44105

Original design application Feb. 27, 1968, Ser. No. 10,743, now Patent No. 212,959, dated Dec. 17, 1968. Divided and this application July 26, 1968, Ser. No. 13,617

Term of patent 14 years

Int. Cl. D11—02

U.S. Cl. D35—3

FIG. 1 is a fragmentary front elevational view of a combined flower pot holder and bracket therefor embodying my new design; and

FIG. 2 is a side elevational view of the combined flower pot holder and bracket therefor of FIG. 1. The design is foreshortened for convenience of illustration and the broken lines are for illustrative purposes only.

This is a division of design application Ser. No. D. 10,743, filed Feb. 27, 1968, now Pat. No. D. 212,959.

I claim:

The ornamental design for a combined flower pot holder and bracket therefor, substantially as shown and described.
